US00D903123S

(12) **United States Design Patent** (10) **Patent No.:** **US D903,123 S**
Farrell (45) **Date of Patent:** **** Nov. 24, 2020**

(54) **ORAL APPLIANCE**

(71) Applicant: **Christopher John Farrell**, Helensvale (AU)

(72) Inventor: **Christopher John Farrell**, Helensvale (AU)

(**) Term: **15 Years**

(21) Appl. No.: **29/671,041**

(22) Filed: **Nov. 21, 2018**

(30) **Foreign Application Priority Data**

May 25, 2018 (AU) 201813153

(51) **LOC (12) Cl.** **24-02**

(52) **U.S. Cl.**

USPC **D24/181**; D24/180

(58) **Field of Classification Search**

USPC D24/180, 181, 194, 176, 177, 178, 179, D24/182, 110, 110.1–110.6, 127, 108; D29/108, 122, 128

CPC A61F 5/566; A61F 2005/563; A61H 2001/0207; A63B 71/085; A63B 2071/086; A63B 71/0054; A61C 7/08; A61C 7/36; A61C 7/143; A61C 7/148; A61C 19/05
